UNITED STATES PATENT OFFICE.

HENRY C. CLARK, OF WILLIAMSBURG, ASSIGNOR OF ONE-HALF HIS RIGHT
TO WILLIAM CLARK, OF BROOKLYN, NEW YORK.

IMPROVEMENT IN COAL-SCUTTLES.

Specification forming part of Letters Patent No. 134,253, dated December 24, 1872.

To all whom it may concern:

Be it known that I, HENRY C. CLARK, of Williamsburg, in the county of Kings and State of New York, have invented a new and useful Improvement in Coal-Scuttles, of which the following is a specification:

The improvement which I have made consists in a coal-scuttle the spout or front whereof has a swell or curved projection at its junction with the bottom, and, rising therefrom vertically about one-third the depth of the scuttle, terminates in a curved spout. The object is to form a round or oval bottom and rim, with the discharge side made both concave and flat on its inner side, with a deep outlet to effect the easy discharge of the coal and prevent it from spilling out at the sides, and thus obtain all the advantages of a continuously-curved front.

In the accompanying drawing, Figure 1 represents a view in perspective of a coal-scuttle embracing my improvement; and Fig. 2, a vertical section of the same.

The scuttle may be made of two or more parts, with that portion A of the discharge-spout which joins the bottom B made of curved or swelling form to adapt it to a round or oval bottom and hoop, and, rising vertically, terminates in a flat bottom, C, curved upward and outward so as to form with the sides D a deep narrow outlet or mouth, E, rendering it very convenient for inserting it within the opening of a stove and preventing all spilling of the

coal. The vertical swelling portion A forms a concave front on the inner side, which rises and terminates in an arched curve, F, with the flat part C, thereby combining a concave front with a convex-curved discharging-spout, which not only renders it more easy for the coal to slide out, but admits of the use of a flat-bottom spout with a round or oval bottom, which is more conveniently made and less expensive than a straight-front bottom; the design of my improvement being to obtain a cheap scuttle having a round or oval interior and bottom with a flat-bottom front and deep discharging-spout, and dispense with the use of a covered mouth. The outward-swelling base of the front also adds strength both to the bottom and the spout and renders the scuttle more durable than when made with a continuous flat or curved front.

Having described my invention, I claim--

The scuttle having its front or discharge side made with an outward bulge or concave lower portion, A, and terminating in a curved front, C, with sides D, and a deep outlet, E, as shown and described.

In testimony whereof I have hereunto set my hand in the presence of two subscribing witnesses this 25th day of November, A. D. 1872.

HENRY C. CLARK.
